UNITED STATES PATENT OFFICE.

DANIEL HOWARD HAYWOOD, OF NEW YORK, N. Y., ASSIGNOR TO
WILLIAM B. WADSWORTH, OF PLAINFIELD, NEW JERSEY.

CUT-OFF SOCKET.

No. 808,656.

Specification of Letters Patent.

Patented Jan. 2, 1906.

Application filed May 11, 1905. Serial No. 260,031.

To all whom it may concern:

Be it known that I, DANIEL HOWARD HAYWOOD, a citizen of the United States of America, and a resident of the city, county, and State of New York, have invented certain new and useful Improvements in Cut-Off Sockets, of which the following is a specification, reference being had to the accompanying drawings, forming a part thereof.

10 My invention relates to improvements in cut-off sockets of the character disclosed and claimed in a copending application by Olaf Saugstad, filed March 18, 1905, Serial No. 250,754. In such application a cut-off socket is shown and described adapted for the reception of a thermostatic regulator when used in connection with hot-water tanks. The cut-off socket has a valve device by which communication can be opened or closed between the water in the tank and the interior of the socket in which is contained the thermostatic portion of the regulator. By this means the regulator may be removed at will without it being necessary to first drain the tank and when replaced may be directly immersed in fluid circulating through the tank.

15 The present invention includes means for automatically opening and closing such communication upon insertion or withdrawal of the regulator, whereby the mere act of inserting the regulator will open circulation from within the tank to within the socket and the mere act of removing the regulator will cause such circulation to cease. When 20 the valve mechanism is thus automatically controlled, the danger of removing the regulator without first turning off the water or of forgetting to turn on the water after the regulator has been inserted is entirely eliminated, as will be well understood, and, further, no 25 instructions will be required to the workmen in removing and replacing the regulator, as all conditions are automatically taken care of.

My form of the device further lends itself 45 to the multiplication of ports without much additional complication, whereby free circulation when the valve is open is insured and such free circulation insured in any position of the socket.

50 My invention further consists in certain novel details of construction and combination of parts, as will be hereinafter more fully pointed out.

In order that my invention may be more fully understood, I will now proceed to describe several forms of cut-off sockets embodying same and will then point out the novel features in claims.

In the drawings, Figure 1 is a view in central longitudinal section through a cut-off socket embodying my invention, showing same in position in a tank and showing also in dotted lines a thermostatic regulator mounted therein. Fig. 2 is a view in central transverse section through the socket, the plane of section being taken substantially on the line 2 2 of Fig. 1. Fig. 3 is a view in central transverse section through the socket, the plane of section being taken substantially on the line 3 3 of Fig. 1. Fig. 4 is a fragmentary view in central longitudinal section, showing a slightly-modified structure. Fig. 5 is an end view of the same. Fig. 6 is a fragmentary view in central longitudinal section of a further-modified structure.

Referring first of all to the form shown in Fig. 1, the socket comprises a shell 1 and a tubular extension 2, closed at the end by a cap 3 or equivalent means. The shell is provided with a screw-threaded portion 4, by which it may be screwed into a corresponding internally-screw-threaded opening in the wall of a tank, boiler, or the like. 5 designates the tank, a portion of which is shown in the drawings. At its outer end the shell 1 is provided with an internally-screw-threaded portion 6, arranged to receive a thermostatic regulator 29, here shown in dotted lines as in operative position. The length of the shell portion 1 may vary as desired. It may be quite short, if preferred; but it is convenient to make it several inches in length, because the tank is usually lagged with asbestos or other covering, and in such case a socket so made brings the head of the regulator out to a convenient position beyond the lagging, as will be readily understood. A valve-casing 7 is fitted to the outer end of the socket-shell 1, being here shown as screwed into the screw-threaded portion 6 and having a flange 8, the end of which is accurately fitted to the shell by means of a ground joint 9 to prevent leakage. Between the flange and the body of the socket-shell is formed an annular channel 10, and connecting with this annular channel 10 are a series of ports or passages 11, affording communication

with the interior of the tank. An annular valve 12 is fitted to a valve-seat 13, formed at the rear end of the valve-casing 7. The said valve opens toward the channels 11 and closes 5 in the opposite direction, whereby pressure of water within the tank will tend to keep the valve closed. A light spring 14 may be employed, if desired, to keep the valve normally in its seat. An operating-ring 15 is fitted to 10 a suitable annular channel in the valve-casing 7 and is connected with the valve 12 by a plurality of stems 16, which pass freely through longitudinal openings 17. The operating-ring 15 projects outwardly beyond the outer face 18 of the valve-casing and in the path of the regulator to be inserted. When the regulator is inserted, it will engage the ring 15, and forcing same inward toward the tank will open the valve 12, thereby opening communication from the tank through the ports or 20 passages 11 to the longitudinal opening 17. Transverse openings 19 allow communication from the openings 17 to the interior of the socket, whereby free circulation is established 25 between the interior of the socket and the interior of the tank whenever the valve 12 is opened. Removal of the regulator will cause the valve 12 to automatically close, the pressure of the water from the tank being sufficient to effect 30 this directly the abutment which engages the ring 15 is removed. The spring 14, if employed, will further assist in this movement.

Preferably I provide a plurality (three or more) of the channels 11 around the socket-body, as shown in Fig. 3, because when so arranged the angular position of the socket with respect to the tank is immaterial—*i. e.*, it is immaterial in screwing the socket into place—as to at what point angularly the socket is 40 finally brought to rest.

In Figs. 4 and 5 I have shown a slight modification in which a plurality of independent valve devices 20 are secured in position around the central opening of the socket, the valve- 45 stems 21 protruding therefrom in the path of the regulator. Each valve device is preferably screwed into an independent recess 22, communicating with a corresponding port or passage 11. A plurality of valve devices are 50 preferably employed, conveniently three, as shown, so as to insure circulation in any position of the socket.

In Fig. 6 a still further modification is shown, in which the socket body or shell is formed in 55 two parts 23 24, the portion 23 constituting the valve-casing. In this instance I have shown a plurality of valves 25 fitted to corresponding valve-seats 26 and with their stems 27 engaging an operating-ring 28, arranged in the path of the regulator when in operative position.

In all forms of the device it will be seen that the following principle remains the same: The screwing of the regulator into place auto-

matically operates the valve mechanism to 65 open communication between the interior of the tank and the interior of the socket, whereby the thermostatic portion of the regulator is immersed in the tank fluid as fully and completely as if the socket were not present, 70 while the unscrewing of the regulator to remove same causes the valve mechanism to close, so as to cut off such communication, whereby escape of water other than the small quantity locked up in the socket itself will be 75 prevented. It will also be seen that the device is inexpensive to manufacture and comprising but few parts will not be liable to get out of order.

What I claim is—

1. In a cut-off socket, the combination with a socket member arranged to removably support a regulator, of means for controlling admission of fluid to the socket, operated by the insertion and removal of the regulator.

2. A cut-off socket comprising a socket member having means for securing same to a tank, and means for removably receiving a regulator therein, and means operated by the insertion and removal of the regulator for controlling admission of fluid to the socket from the tank.

3. A cut-off socket having a portion adapted to enter a tank, and provided with means for securing it to the tank, said socket adapted and arranged to removably support a thermostatic device, and provided with means operated by the insertion and removal of the thermostatic device for controlling admission to the socket of fluid from the tank.

4. A cut-off socket comprising a shell adapted to be secured to the wall of a tank, and a tube adapted to extend inward within the tank, said socket adapted and arranged to removably support a regulator, and provided with means operated by the insertion and removal of the regulator for controlling admission to the socket of fluid from the tank.

5. A cut-off socket comprising a shell adapted to be secured to the wall of a tank, and a tube adapted to extend therefrom inward within the tank when in position therein, said shell having an internally-screw-threaded portion adapted for engagement with the correspondingly-screw-threaded portion of the temperature-regulator; and means operated by the insertion and removal of the temperature-regulator for controlling admission to the socket of fluid from the tank.

6. The combination with a tank and a thermostatic device extending therein, of a cut-off socket surrounding the portion of the thermostatic device in the tank, and means operated by the insertion and removal of the thermostatic device for controlling admission of fluid to the socket from the tank.

7. The combination with a tank of a socket extending within same, a thermostatic device removably fitted to said socket, and means op-

erated by the insertion and removal of the thermostatic device for controlling admission to the socket of fluid from the tank.

8. In a cut-off socket, the combination with a shell arranged to receive a thermostatic device, and a valve arranged to control admission of fluid to the interior of the shell, said valve having a portion arranged in the path of the thermostatic device, when same is being inserted.

9. In a cut-off socket, the combination with a shell arranged to receive a thermostatic device, of a valve-casing fitted thereto, a valve in said casing arranged to control admission of fluid to within the socket, and an operating

member for said valve arranged to be engaged by said thermostatic device while it is being inserted.

10. In a cut-off socket, the combination with a socket member or shell arranged to removably support a regulator, said shell provided with a plurality of circulating-passages, of valve mechanism controlling said passages, and operated by the insertion and removal of the said regulator. 20

DANIEL HOWARD HAYWOOD.
